(57) **CLAIM**

I claim the ornamental design for the safety razor cartridge, as shown and described.

DESCRIPTION

FIG. 1 is a lower perspective view of a safety razor cartridge. FIG. 2 is an upper perspective view thereof.

FIG. 3 is a rear view thereof.

FIG. 4 is a front view thereof.

FIG. 5 is a left side view of FIG. 3.

FIG. 6 is a right side view of FIG. 3.

FIG. 7 is a top view thereof; and,

FIG. 8 is a bottom view thereof.

The broken line in the figures is for the purpose of illustrating portions of the safety razor cartridge and forms no part of the claimed design.
